UNITED STATES PATENT OFFICE

GEORGE E. VANCE, OF SPRINGFIELD, OHIO, ASSIGNOR TO THE SAFETY GRINDING WHEEL & MACHINE COMPANY, OF SPRINGFIELD, OHIO, A CORPORATION OF OHIO

GRINDING WHEEL

Application filed June 24, 1929. Serial No. 373,077.

This invention relates to grinding wheels, it more particularly relating to that type of wheel in which the abrasive element is clamped between a pair of safety collars 5 mounted upon the shaft of the wheel.

Heretofore it has been the practice to employ solid cast iron or cast steel clamping collars to not only secure the abrasive element on the shaft of the wheel, but also prevent 10 pieces of the abrasive element from flying outwardly by centrifugal force in case of breakage. It has been found that when such collars are employed in large size wheels, particularly high-speed wheels, the weight of 15 the collars is so great as to make it impossible to maintain the proper speed.

The object of my invention is to provide collars so constructed as to maintain the proper rigidity and strength but also eliminate 20 excessive weight so that the proper speed of the wheel may be secured.

Referring to the drawings:

Fig. 1 is a vertical section of a wheel embodying my improvements, the section being 25 on the line 1—1 of Fig. 2.

Fig. 2 is a side elevation.

Fig. 3 is a vertical section of a modified form of wheel, the section being on the line 3—3 of Fig. 4.

Fig. 4 is a side elevation of the modification 30 partly broken away.

Fig. 5 is a vertical section of a portion of a clamping collar showing another modification.

Fig. 6 is a side elevation of a portion of a wheel in which the modified form of clamping collar shown in Fig. 5 is employed.

Referring first of Figs. 1 and 2, 1 represents the shaft of a grinding wheel, 2 a centering 40 hub mounted on the shaft, 3 the abrasive element which is formed in any usual and well known manner of abrasive material, 4 the collars, 5 suitable washers, and 6 a nut threaded on the shaft. In this construction each 45 of the collars is a casting which is cored out to form in effect a pair of disks with radially-extending spacing, connecting and strengthening ribs 7 of any suitable number therebetween. This construction not only gives the 50 required rigidity and strength but furnishes

the desired degree of lightness. Preferably the inner disk of each collar is cast with openings 8 to permit the removal of the sand and the collars are converged toward the peripheries to accommodate them to the tapered 55 abrasive element to furnish the desired degree of safety.

In Figs. 3 and 4 there is shown a modification in which these clamping collars indicated at 4' are formed with inner shoulders 9 upon which the abrasive element 3 is seated and centered, thus eliminating the separate hub member 2. The collars in this modification are otherwise constructed like the collars shown in Fig. 1 in that they are cast 60 with inner and outer disks with interior strengthening, spacing and connecting ribs 7.

In Figs. 5 and 6 there is shown a clamping collar of a built up character in which two 70 sheet metal disks 10 and 11 are spaced apart by a series of metal ribs 12, the disks and ribs being connected together by rivets 13.

By this construction, a clamping collar of the desired rigidity, strength and lightness is 75 provided which can be applied to large size, high speed grinding wheels without interference with the proper speed of the wheel.

Having thus described my invention, I 80 claim:

In a grinding wheel, an annular tapered abrasive element, and a pair of clamping collars one on each side of said element to clamp said element therebetween, each of said collars being formed of two sheet metal disks 85 and a series of separate radially-extending ribs therebetween, together with means for connecting the disks and ribs together.

In testimony whereof, I have hereunto set 90 my hand this 21st day of June, 1929.

GEORGE E. VANCE.
